UNITED STATES PATENT OFFICE

FRANK A. VAN BEZEL, OF EL CENTRO, CALIFORNIA, ASSIGNOR TO DUAL AIRCRAFT MOTORS INC., LTD., OF EL CENTRO, CALIFORNIA

MANIFOLD

Application filed July 11, 1930. Serial No. 467,361.

This invention relates to manifolds for internal combustion engines and is especially designed for use upon airplane engines.

An object of the invention is to provide means in the construction and arrangement of the intake and exhaust manifolds, whereby heat from the exhaust gases will heat the fuel mixture as it passes through the intake manifold and thus eliminate to a large degree the condensation of fuel in its passage from the carburetor to the engine cylinders, and thus provide a more perfect fuel which will result in increased efficiency of the engine and permit of the use of a lower grade of fuel than is ordinarily used in airplane engines.

In the operation of airplane engines, the intake manifold is subjected to the action of a terrific rush of air from the airplane propellers, so that fuel of a high test must be used and this fuel is usually heated before it reaches the intake manifold.

In the present invention the fuel is heated as it passes through the intake manifold into the engine cylinders, the said manifold being maintained at a temperature to properly heat the fuel, so that the latter will enter the cylinders in a highly atomized state and will provide proper combustion. At the same time, means are provided to prevent overheating of the fuel so that the latter will not be ignited in the manifold.

With the above and other objects in view, the invention further includes the following novel features and details of construction, to be hereinafter more fully described, illustrated in the accompanying drawings and pointed out in the appended claims.

In the drawings:—

Figure 1 is a top plan view of a combined intake and exhaust manifold constructed in accordance with the invention.

Figure 2 is an inner face view of the same.

Figure 3 is a bottom plan view.

Figures 4 and 5 are sectional views taken respectively on the lines 4—4 and 5—5 of Figure 2.

Figure 6 is a sectional view on the line 6—6 of Figure 1.

Referring to the drawings in detail where-
50 in like characters of reference denote corre-

sponding parts, the reference character 10 indicates an exhaust manifold which is constructed of any suitable material and may be of any suitable shape. This manifold is provided with spaced ports 11 whose number may conform to the number of cylinders of the engine with which the manifold is to be used. The manifold 10 is provided with an outlet 12 through which the exhaust gases pass.

The exhaust manifold is preferably cross sectionally flat as shown in Figure 6 of the drawings and the intake manifold is also cross sectionally flat and includes a fuel intake passage 13 and a fuel distributing passage 14. The passage 13 is provided at its outer end with a flange 15 by means of which a carburetor (not shown) may be attached, while the inner end of the passage 13 communicates with the passage 14 as shown at 16. This point of communication is substantially central of the length of the passage 14 so that the fuel may pass in opposite directions to ports 17 for entrance into the cylinders of the engine. The ports 11 and 17 are relatively offset and are surrounded by flanges 18 to provide means for attaching the manifold to the engine.

As shown in the drawings, the exhaust manifold is positioned beneath the intake manifold and the adjacent walls of these manifolds are slightly spaced apart so as to provide an air chamber 19. A wall 20 extends along the outer edge of this chamber and provides connection between the manifolds along one edge thereof, while the flanges 18 serve to connect the manifolds along the opposite edge. In addition, the wall 20 closes the outer edge of the chamber 19 and prevents the entrance into this chamber of air directed rearward from the airplane propeller as indicated by the arrow *a* in Figures 1 and 3 of the drawings.

By spacing the adjacent walls of the manifolds apart and providing the air chamber 19, heat from the exhaust gases passing through the chamber 10 will heat the intake manifold sufficiently to provide proper vaporization of the fuel passing therethrough, so that the fuel will enter the engine cylin- 100

ders in a highly atomized state. This is in contradistinction to the method ordinarily used in airplane engines for heating the fuel before it enters the intake manifold, and as the latter is subjected to the action of the propeller, the temperature of the fuel will be immediately lowered when it reaches the intake manifold. Through the use of the present invention, a much lower test fuel may be used than is ordinarily used in airplane engines.

By spacing the adjacent walls of the intake and exhaust manifolds, overheating of the intake manifold and consequent overheating of the fuel therein, as would be the case if the manifolds were separated by a single wall, is prevented. Thus reduction of power due to overheated fuel is obviated.

The invention is susceptible of various changes in its form, proportions and minor details of construction and the right is herein reserved to make such changes as properly fall within the scope of the appended claims.

Having described the invention what is claimed is:

1. A combined intake and exhaust manifold comprising walls defining a fuel intake passage, spaced ports communicating with said passage of elongated formation, separate spaced walls defining an exhaust passage, and spaced ports communicating with the exhaust passage, the space between the adjacent walls of the intake and exhaust passages defining an air chamber between the passages, these passages being in overlapped relation to each other.
2. A combined intake and exhaust manifold comprising walls defining a fuel intake passage and adapted to have one end in communication with a source of fuel supply, a fuel distributing passage in communication with the other end of the intake passage, spaced ports for the fuel distributing passage for communication with the intake ports of an engine, spaced walls defining an exhaust passage, spaced ports for the exhaust passage, the space between the adjacent walls of the intake and exhaust passages defining an air chamber, and a wall extending along the outer edge of the air chamber and connecting the adjacent walls of the intake and exhaust passages, said passages being disposed in overlapping relation to each other.

In testimony whereof I affix my signature.
FRANK A. VAN BEZEL.
